UNITED STATES PATENT OFFICE.

FRANK CONRAD, OF PITTSBURGH, AND J. STANLEY KINNEY, OF WILKINSBURG, PENNSYLVANIA, ASSIGNORS TO WESTINGHOUSE ELECTRIC AND MANUFACTURING COMPANY, A CORPORATION OF PENNSYLVANIA.

SPARK-ADVANCING MECHANISM.

Application filed April 14, 1920. Serial No. 373,845.

To all whom it may concern:

Be it known that we, FRANK CONRAD, a citizen of the United States, and a resident of Pittsburgh, in the county of Allegheny and State of Pennsylvania, and J. STANLEY KINNEY, a citizen of the United States, and a resident of Wilkinsburg, in the county of Allegheny and State of Pennsylvania, have invented a new and useful Improvement in 10 Spark-Advancing Mechanisms, of which the following is a specification.

Our invention relates to ignition systems for internal-combustion engines and particularly to mechanisms for controlling the time 15 of the spark in an ignition system.

One object of our invention is to provide means that shall advance or retard the spark in an ignition system for an automobile in a simple and efficient manner and that shall be 20 easily controlled at all times by the operator of the automobile.

In manually controlling the adjustment of the spark in an ignition system for the internal-combustion engine of an automobile, 25 trouble is often encountered in effecting an accurate adjustment, inasmuch as it is difficult, in many systems, to change the degree of advance by small increments.

In an ignition system provided with mechanism constructed in accordance with our invention for advancing the spark, a differentially-movable member is provided for so controlling the driving means for the timing mechanism as to permit the adjustment 30 of the spark by very small increments. In the preferred form of practicing our invention, the generator, which is connected to the internal combustion engine, is joined to the timing mechanism of the system by a worm 35 member and a worm wheel. The worm wheel is directly connected to the timing mechanism, and the worm member is slidably mounted upon the shaft of the generator. The worm member is provided with 40 a sleeve having spiral slots formed in it, and the generator shaft is provided with pins which project into said slots for effecting a spiral movement of the worm member when it is moved along the generator 45 shaft.

In order to vary the position of the timing mechanism relative to the engine, the worm member is moved along the generator shaft. If the worm member were moved linearly

along the generator shaft, the advance of 55 the spark would be effected at too rapid a rate to permit a very accurate adjustment. However, the pin-and-groove connection between the generator shaft and the worm member modifies and opposes the action of 60 the worm member in varying the degree of advance. Thus, a differential movement of the worm member is effected which permits varying the time of the spark by small increments. 65

In the accompanying drawing, Figure 1 is a side elevational view, partially in section, of an ignition mechanism constructed in accordance with our invention, and Fig. 2 is an end elevational view, partially in 70 section, of the mechanism shown in Fig. 1.

Referring to the drawing, a generator 1, comprising a frame 2 having an extension casing 3 and a shaft 4, is connected, in any suitable manner, to an internal-combustion 75 engine (not shown.) The shaft 4 of the generator is connected to the timing mechanisms 5 and 6 in a manner to permit an accurate adjustment of the time of the spark in the ignition system for the engine. 80

The timing mechanisms 5 and 6 are directly mounted upon the extended portion 3 of the generator frame, and the shaft 7 of the timing mechanism 6 is connected to the generator 4 by means of a worm wheel 8 and a worm member 9. The worm wheel 8 is directly mounted upon the shaft 7. The worm member 9 is slidably mounted upon the shaft 4 and is connected to it by a pin-and-groove connection. The worm member comprises a sleeve 10, which has spiral slots 11 and 12, and a grooved collar 13 which is disposed adjacent to teeth 14 of the worm. The shaft 4 is provided with pins 15, one only of which is illustrated, for projecting into the slots 11 and 12 formed in the sleeve 10 of the worm member. A fan member 16 is mounted upon the collar 13 for maintaining a circulation of the oil contained in the casing 3. 90

The timing mechanisms 5 and 6 may be of any suitable construction and, inasmuch as the means for operating the timing mechanism 5 is similar to the means for operating the timing mechanism 6, the construction and operation of only one means will be completely described, namely, the connecting means between the timing mechanism 6 and 100 105

the generator shaft 4. It may be noted, however, that the timing mechanism 5 is provided with a shaft 17 and a worm wheel 18, which is connected to the worm member 9.

The adjustment of the spark in the ignition system is controlled by a lever 19 which is mounted upon a short shaft 20. The shaft 20 is provided with any suitable bearings 10 upon the casing 3 and carries a yoke member 21 which is provided with sliding block members 22 that operate in the groove of the collar 13. Thus, if the lever 19 is operated in a forward or in a reverse direction, the 15 yoke 21 and the blocks 22 operate upon the collar 13 to move the worm member 19 along the generator shaft 4. Such movement of the worm member 9 along the generator shaft varies the position of the worm wheel 8 relative to the shaft 4 and, accordingly, effects a variation in the time of the spark of the ignition system. If the worm member 9 were moved linearly along the shaft 4, the variation would be large for a very small 25 movement of the worm 19 and, accordingly, it would be difficult to effect an accurate adjustment of the spark. However, by providing a pin-and-groove connection between the worm member 9 and the generator shaft 4, a 30 differential movement of the worm member is effected and the action of the worm member is so modified as to permit small changes in the spark advance for relatively large movements of the lever 19. The lever 19 35 may be controlled, in any suitable manner, by the operator of the vehicle.

Modifications in the system and in the arrangement and location of parts may be made within the spirit and scope of our invention and such modifications are intended 40 to be covered by the appended claims.

We claim as our invention:

1. In an ignition system, the combination comprising a worm wheel, a worm member 45 in engagement with said wheel, a shaft for supporting said worm member, and means comprising a pin carried by said member and a spiral groove in said shaft for connecting said worm member to said shaft.

50 2. In an ignition system, the combination comprising a worm wheel, a driving shaft, and a worm member having a pin-and-spiral-groove connection to said shaft and slidable along the shaft while meshing with said 55 worm wheel.

3. In an ignition system, the combination comprising a worm wheel, a driving shaft, a worm member mounted on said shaft and effecting engagement with said worm wheel, 60 and means comprising pins projecting from said shaft and operating in spiral grooves formed in said worm member for joining the worm member to the shaft.

4. In an ignition system, the combination 65 with a generator, and an ignition device

driven thereby, of a worm member movable along the generator shaft for varying the time of the spark in the system controlled by said device, and connecting means between said worm member and the generator 70 shaft for modifying the effect caused by the movement of the worm member along the shaft.

5. In an ignition system, the combination comprising a driving shaft, a worm member 75 slidably mounted upon said shaft, a worm wheel in engagement with said worm member, control means for moving the worm member along the shaft to change the position of the worm wheel relative to the shaft, 80 and the connecting means between said worm member and the shaft for modifying the effect of said control means.

6. In an ignition system, the combination comprising a driving shaft, an ignition device having a driven shaft, a worm wheel on said driven shaft, a worm member in engagement with said worm wheel and slidable along said driving shaft for varying the relative angular positions of the said 85 shafts, and a pin-and-groove connection between the worm member and said shaft for modifying the effect on the relative positions of the shaft and the worm wheel 90 caused by the movement of the worm member 95 along the shaft.

7. In an ignition system for an internal-combustion engine, the combination comprising a generator propelled by the engine, a sleeve mounted on the shaft of said generator and having spiral slots therein, pins projecting from the generator shaft through the slots in said sleeve, a worm rigidly mounted on said sleeve, a worm wheel meshing with said worm, and a timing mechanism 100 operated by said worm wheel. 105

8. In an ignition system for an internal-combustion engine, the combination comprising a generator propelled by the engine, a worm member slidably mounted upon the 110 shaft of said generator and having spiral grooves, pins projecting from said shaft and engaging said spiral grooves for effecting a spiral movement of the worm member along the shaft, a worm wheel in engagement with 115 said worm, and a timing mechanism operated by said worm wheel.

9. In an ignition system for an internal-combustion engine, the combination comprising a timing mechanism, a driving shaft, 120 a worm wheel and a worm member for connecting said timing mechanism to the driving shaft, control means for moving the worm member along the shaft relative to the worm wheel to vary the timing of the sparking impulses, and connecting means between said shaft and the worm member for modifying the effect of the action of said control means. 125

10. In an ignition system for an internal- 130

- combustion engine, the combination comprising a timing mechanism, a shaft for operating said mechanism in accordance with the operation of the engine, a worm wheel 5 connected to said mechanism, a worm member mounted on said shaft and in engagement with said worm wheel, control means for moving said worm member along the shaft to change the position of the timing mechanism relative to the shaft, and a pin-and-groove connection between the worm member and the shaft for modifying the effect of the action of said control means. 10
11. In an ignition system for an internal-combustion engine, the combination comprising a driving shaft, a timing mechanism, a gear member mounted on said shaft, a gear wheel connected to said mechanism and meshing with said gear member, and means 15 whereby movement of said gear member along said shaft effects relative angular movement therebetween to vary the time of the spark in the system. 20
12. In an ignition system for an internal-combustion engine, the combination comprising a timing mechanism, a driving shaft, means comprising gear wheels for connecting said mechanism to the shaft and means whereby axial movement of one of said gear 25 wheels on said shaft effects relative angular movement therebetween to vary the adjustment of the spark in the system. 30
13. In an ignition system for an internal-combustion engine, the combination comprising a driving shaft, a timing mechanism, a worm member mounted on said shaft, a worm wheel connected to said mechanism and meshing with said worm member, means for simultaneously effecting move- 35
- ment of said worm member along, and angular movement relatively to, said shaft to vary the adjustment of the spark in the system, and means mounted on said driving shaft for supplying lubricant to said worm wheel and the worm member. 40
14. The combination with a driving and a driven shaft, of a gear mechanism for operatively connecting said shafts, a member of said mechanism having a connection to one of said shafts whereby axial motion of said member effects angular movement of said member relatively to said shaft and to a coacting member of said mechanism. 45
15. The combination with a driving and a driven shaft, of a gear mechanism for operatively connecting said shafts, a member of said mechanism having a connection to one of said shafts whereby axial motion of said member effects angular movement of said member in different degrees relatively to said shaft and to a coacting member of 50 said mechanism. 55
16. The combination with a driving and a driven shaft, of a gear mechanism for operatively connecting said shafts, a member of said mechanism having a connection to one of said shafts whereby axial motion of said member effects angular movement of said member relatively to said shaft and to a coacting member of said mechanism, said 60 relative movements being in such directions as to tend to produce opposite adjustment of the relative angular positions of said shafts. 65
- In testimony whereof, we have hereunto subscribed our names this 1st day of April, 1920. 70
- FRANK CONRAD.
J. STANLEY KINNEY. 75
